UNITED STATES PATENT OFFICE.

ELISHA SHERMAN, OF LEAVENWORTH, KANSAS.

TRAP-TARGET.

SPECIFICATION forming part of Letters Patent No. 595,738, dated December 21, 1897.

Application filed January 13, 1897. Serial No. 619,030. (No model.)

To all whom it may concern:

Be it known that I, ELISHA SHERMAN, a citizen of the United States, residing at Leavenworth, in the county of Leavenworth and State of Kansas, have invented a new and useful Trap-Target, of which the following is a specification.

This invention relates to trap-targets.

The object of the invention is to provide a trap-target of simple inexpensive construction and arrangement and wherein breakage is insured in case it is struck by a shot and which is substantial and strong at the point where it is held in the trap.

15 The invention consists, substantially, in the construction, combination, location, and arrangement, all as will be more fully herein-after set forth, as shown in the accompanying drawings, and finally specifically pointed out 20 in the appended claims.

25 Referring to the accompanying drawings and to the various views and reference-signs appearing thereon, Figure 1 is a view in top plan of a trap-target embodying the principles of my invention. Fig. 2 is a transverse sectional view of the same.

When a trap-target is introduced to a trap preparatory to being thrown, the clamping jaws or fingers of the trap grasp the target on 30 the lower edge or rim A thereof and at approximately diametrically opposite points. When the trap is sprung, the forward impetus frees the target from the forward finger or jaw of the trap, and for an instant the entire force of the impetus of the trap is imposed on the target at the point of contact with the edge or rim A thereof of the rear finger or jaw of the trap. It is important, therefore, to strengthen the target at this point in 35 order to avoid the danger of breaking said target at this point as it leaves the trap. The first part of my invention is directed to this object, and in order to accomplish the object desired I increase the thickness of the target 40 at this point, as indicated at B, and instead of forming the edge or rim A with a square shoulder on the inside, as heretofore has been the case, I so form the molds in which the target is made as to leave a curved surface C 45 on the inside of the rim instead of the squared shoulder, as formerly. Thus not only am I enabled to thicken the rim or edge A at this

point by introducing more material, but the tendency and liability to break at this point are also lessened by reason of the curved outline of the inner surface thereof, as will be readily seen.

55 Heretofore trap-targets have been made substantially dish shape, and if struck by a shot on the outer curved surface thereof while soaring it frequently happens that the shot glances off without effecting a breakage of the target, and hence without effecting a score for the marksman. It has been endeavored to overcome this objection by providing circular and concentric raised ridges on the outer surface of the target, the thickness of the body of the target being otherwise substantially uniform throughout. This has not proven entirely satisfactory, for the reason that the shot would frequently merely chip off the raised ridge without otherwise breaking the target, or perhaps would merely perforate the body of the target without otherwise destroying it, and hence would pass as 70 a miss. The next feature of my invention is designed to overcome this difficulty, and the desired object of the invention is secured by providing the body of the target with a series of grooves D, nearly, but not quite, penetrating 75 the said walls. These grooves may be arranged in any suitable or desired manner, the generic idea being to provide such grooves in the body of the target, so as to insure a breakage and destruction of the target when 80 struck by a shot. In the form shown, to which, however, I do not desire to be limited or restricted, said grooves are arranged on the inside of the body of the target and in concentric circles, and, if desired, may be arranged in the under or inner surface of the target at points opposite the raised ribs or ridges E on the outside thereof. From this 85 construction and arrangement it will be seen that when a shot strikes the target, or when 90 it strikes a raised rib or ridge E on the outer surface thereof, the shock of the impact causes the body of the target to fracture and separate into distinct pieces along the lines of one of the grooves D, thereby destroying the target, the thin fragile connection through the wall of the target left by the grooves D facilitating such fracture and separation. 95 Heretofore it has been the custom to de- 100

press the top of the target below the surface of the surrounding rim. The object was to avoid the liability of the shot glancing off in case it struck the top surface without resulting in a breakage of the target. In such cases a shot striking the top surface of the target would either penetrate such top or else would glance until it encountered the surrounding wall of the depressed top and then penetrate such wall without otherwise defacing or injuring the target. The next feature of my invention is directed toward avoiding this defect and at the same time providing a target of such construction that a shot striking the top would effect a breakage. To this end I provide the target with a raised top F, and I so construct the molds in which the targets are made that the top F is thicker and hence stronger than the other portion of the body. From this it will be seen that in case a shot should strike the outer wall G of the top, instead of merely perforating said wall or merely removing the top, its increased strength will resist the force of the impact of the shot, and hence the fracture will occur at the more fragile point of the grooves D. In order that the shot after striking the upper surface of the top may not then glance off without effecting a breakage of the target, I provide a suitable configuration in said top. This configuration may take any desired form. In the drawings I have shown a depressed star-shaped figure which answers the purpose, but I desire it to be understood that I do not limit or confine myself thereto.

It will be understood that targets embodying my invention are most cheaply and expeditiously manufactured with molds into which the composition is placed.

From the foregoing description it will be seen that I produce a target that is simple, cheap, and efficient.

Having now set forth the object and nature of my invention and a construction and arrangement embodying the same, and having explained such construction and its function and mode of operation, what I claim as new

and useful and of my own invention, and desire to secure by Letters Patent of the United States, is—

1. A trap-target having a plurality of raised ribs circularly arranged on the outer surface thereof, and corresponding circularly arranged grooves in the inner surface thereof, as and for the purpose set forth. 50

2. A trap-target having a plurality of raised ribs concentrically arranged on the outer surface of the body thereof, and corresponding concentrically-arranged grooves on the inner surface of such body, each of said grooves 60 nearly but not quite penetrating the body of such target, as and for the purpose set forth.

3. A trap-target having a body part, a rim, and a top, the walls of said rim and top being thicker than the wall of the body part, said 65 body part provided with a plurality of concentric raised ribs on the outer surface thereof, and corresponding grooves on the inner surface thereof, each of said grooves nearly but not quite penetrating the wall of such body, 70 as and for the purpose set forth.

4. A trap-target comprising a body part, a thickened rim, and a top, the inner surface of the joint between such rim and body part being curved, and annular raised ribs on the 75 exterior surface of the body part, and annular grooves on the inner surface of the body part, each of said grooves nearly but not quite penetrating the wall of such body part, as and for the purpose set forth. 80

5. A trap-target having a plurality of raised ribs on the outer surface thereof and grooves on the inner surface thereof, said grooves corresponding and arranged adjacent to said ribs, and nearly but not quite penetrating 85 the wall of the target, as and for the purpose set forth.

In witness whereof I have hereunto set my hand this 9th day of January, 1897, in the presence of the subscribing witnesses.

ELISHA SHERMAN.
